UNITED STATES PATENT OFFICE.

KOBY KOHN, OF NEW YORK, N. Y.

SAFETY FIRECRACKER.

Application filed December 22, 1924. Serial No. 757,561.

To all whom it may concern:

Be it known that I, KOBY KOHN, a citizen of the United States, and residing at New York, county of New York, State of New York, have invented certain new and useful Improvements in Safety Firecrackers, of which the following is a specification.

This invention relates to pyrotechnics and more particularly to firecrackers of the 10 safety type.

It is the general object of this invention to provide a novel and improved form of safety firecracker.

More particularly it is an object of this 15 invention to provide a firecracker which may be safely held in the hand during the explosion without injury to the person.

Another object of the invention consists in the provision of a safety firecracker having 20 an explosive charge therein, with the wall of the firecracker weakened between the charge and the end opposite the fuse, so that upon explosion the fuse end of the firecracker will be blown off at the weakened 25 section, so that in case the user fails to let go of the firecracker, he will not be injured.

Still another object of the invention consists in the provision of a safety firecracker including a tubular casing, having a charge 30 of explosive material therein, a fuse extending into said charge and projecting from one end of the firecracker, and a weakened section in the wall of the firecracker between said charge and the end opposite to the fuse, with means between the weakened portion 35 of the wall and said opposite end for preventing gases from blowing back toward that end.

In the accompanying drawings and following specification there is disclosed, by way of example, only, a single embodiment of the present invention, it being understood, however, that various changes and modifications may be made in the arrangement, 40 material, size and proportion of the various parts, without departing from the spirit of the invention as set forth in the attached claims.

In said drawings:

Figure 1 is a side elevation of the preferred form of a safety firecracker constructed according to this invention.

Figure 2 is a longitudinal central section thereof.

Figure 3 is a transverse section taken on line 3—3 of Figure 2.

Figure 4 is a longitudinal central section of a modified form of safety firecracker.

Figure 5 is an elevation of a further modification, and

Figure 6 is a longitudinal central section of still another modified form of safety firecracker.

It is well-known that the ordinary firecracker or salute, as it is sometimes known, is not considered safe, especially in the hands of children or irresponsible persons. This is mostly because of the danger of the firecracker exploding while still held in the hand. It is the usual practice to hold the 70 firecracker by the end remote from the fuse with one hand while lighting the fuse from a match or other source of fire held in the other hand, and it may be that the fuse acts quicker than expected, or that the user's attention is distracted, and the firecracker explodes in his hand, resulting in painful injuries if not the loss of several fingers. The present invention contemplates overcoming these difficulties by providing a safety firecracker in which the charge is confined near 75 the end containing the fuse and by providing a weakened section in the side walls just behind the charge-containing section. Additional protection against gases blowing 80 back and injuring the hand is afforded by a plug or cap closing the tube behind the weakened section, or by baffles tending to prevent the major portion of any gas which blows back from coming in contact with 85 the hand. Additional safety means are provided in the form of gas vents to allow the force of the explosion to be largely dissipated laterally.

Referring to the drawings there is disclosed in Figures 1, 2 and 3 a safety firecracker, or salute, composed of a paper or pasteboard tube, or tubular member 10, having walls of such thickness as to be dis- 90 ruptable by the explosive charge contained 95 therein, and yet of sufficient strength to afford a considerable confinement of the charge to increase the noise of the detonation. This tube may be of any desired length and diameter, depending upon the 100 quantity of charge it is desired to place in it. Near one end is the compartment 11, defined by the caps or plugs 12 and 13, in which all of the charge of the explosive mixture is placed. This charge may or may 105 not fill completely this compartment. A fuse 14 is passed through the outer cap or

partition 13 as shown, which partition may be held in place by an adhesive, or by crimping the end of the tube over it as shown at 15. The fuse passes through a central aperture punched or pressed in the cap 13 and is knotted on the inside as shown at 16 to prevent it from being pulled out. By punching or pressing the hole in the cap 13 to admit the fuse, the walls 13' of the hole are turned inward as shown, so that any attempt to pull the fuse outward, or the pressure of the explosion, only effects a better seal between the cap 13 and the fuse 14, resulting in a louder detonation.

15 The wall of the tube 10 adjacent the cap or partition 12 is weakened by providing it with a plurality of perforations 19 and 20. The walls of the perforations 20 are pressed inward, as clearly shown, instead of punching the hole cleanly, so as to form stops to limit the inward movement of the partition 12 when it is being placed in position, before the end 15 of the tube is crimped over. The partition 12 is preferably fastened in position by an adhesive. The weakened portion of the wall 10 of the tube permits the forward part of the tube containing the explosive mixture compartment 11 to be blown off and free from the rear end of the tube at the 25 time of the explosion, and the shape of the partition 12 materially assists in this effect. It will be noted that any direct rearward pressure on the inturned bottom 17 of the cap effects a toggle action tending to expand 30 the wall 18 of the partition 12 in a radial direction, which force is transmitted to the wall 10 just in front of the weakened section, thus assisting in tearing the wall 10 between the perforations 19 and 20. This 35 shape of the partition 12 as well as that of the partition 13 is effective, to a large extent, in preventing forward and rearward movement during the explosion, confining the majority of the force thereof to a lateral or 40 radial direction.

To prevent any of the gases of the explosion, or the force thereof, which may escape by the partition 12, blowing back through the tube and injuring or burning 45 the user's hand, the additional cap or partition 21 may be provided, secured by an adhesive closely behind the weakened section. This cap or partition 21 is substantially similar in shape to that of the partition 12, the 50 inturned bottom, however, being more exaggerated and the side wall 22 being longer to positively effect an expanding action in a radial direction as explained in connection with the partition 12. Any radial pressure, 55 it will be noted, against the wall 22 will expand it into closer contact with the tube 10, and thus cause it to disrupt in front of the partition 21. The perforations 19 and 20 also act as gas vents to prevent the force 60 of the movement of the partition 12, result-

ing from the explosion, from being transmitted directly to the partition 21, which is itself maintained against rearward movement in the tube 10, by means of the indentations or depressions 23 in the tube 10 just behind this partition. It will thus be seen that the user's hand which is placed at the rearward end of the tube 10 in holding the firecracker is still protected against any of the force of the explosion or from any gas blowing back against it, and thus while the firecracker is not intended to be held in the hand while exploding, in case it accidentally should be, no harm would result.

16 In the event that the partition 12 should be disrupted or blown backward, and its toggle action thus vitiated, the partition 21 acts as a reinforcement thereto, and confines the force of the explosion to the forward end of the tube 10, so that it will be separated at the weakened section formed by the perforations 19 and 20.

The modification disclosed in Figure 4 is identical with that disclosed in Figures 1, 2 and 3 as regards the construction of the chamber 11 for containing the explosive compound, but the partition 24 which corresponds to the partition 21 in the preferred modification has been moved to the rear end 95 of the tube and is maintained in place in the same manner by the indentations or inwardly pressed projections 25 in the wall of the tube 10 and an adhesive. It has not been found necessary to make the side walls 26 of the partition as deep as in the preferred form. As an additional protection to the user, a series of holes or gas vents 27 have been made in the wall of the tube 10 at a position intermediate between the weakened portion, caused by the holes 19 and 20, and the partition 24, to further assist in allowing the gases resulting from the explosion to escape in a lateral direction.

The compartment 28 contained between the partitions 12 and 24 forms in effect an air cushion, having relief means such as the vents 27, which is between the explosive chamber and the user's hand, thus effecting, in a simple and positive manner, the protection of the person from the force of the explosion. Any number of series of vents 27 may, if desired, be arranged in the walls of the compartment 28.

The modification disclosed in Figure 6 is similar, as regards the compartment 11 for retaining the explosive mixture, to the preferred modification and to that modification disclosed in Figure 4, being provided with the holes 19 and 20 to weaken the wall 10 just behind the explosive containing compartment. The remainder of the tube is, however, provided with a plurality of baffles which do not entirely close the tube, but which materially reduce the amount of gas, resulting from the explosion, which can

pass back through it. These baffles 29 and 30 are arranged in circumferential groups and are formed by punching or cutting three sides of a rectangle with the rearward side 5 retained integral with the tube 10, so that a tab can be pushed inward as shown. Where two sets of the baffles, as 29 and 30, are provided, they are arranged in staggered circumferential relation, any desired number 10 of baffles being provided in each set. Between the sets of baffles a series of vents 27, as in the previously described modification, may be provided for the purpose explained in connection with that modification.

15 The baffles 29 and 30 each project inwardly and forwardly, and when impinged on by the gases escaping in a rearward direction through the tube, are bent inwardly so that their tops cooperate with each other 20 and form a substantial closure for the tube, preventing all but a small part of the gases and débris from passing therethrough. By being arranged in a staggered relation, the second set of baffles will more directly receive 25 the force of the gases escaping between those of the first set and thus the amount of gas which escapes from the end of the tube will be inconsequential.

In Figure 5 is disclosed a slight variation 30 which may be applied to any of the previously described modifications. It merely consists in covering the tube 10 with a thin paper or tissue 31, which may, if desired, be in any color or colors, either solid, striped 35 or variegated. This paper will not in any- wise affect the previously described opera- 40 tion of the firecracker. The sole purpose of this covering is to hide the holes or vents in the tube to give the firecracker a more finished and salable appearance, as well as allowing the main tube 10 to be made of cheaper and coarser material. Of course, if desired, this covering paper or tissue may have printed thereon any suitable advertising matter such as the name of the fire- 45 cracker, the name of the manufacturer etc.

Having thus described the invention, what is claimed as new and desired to be secured by U. S. Letters Patent is:

50 1. An article of the character described comprising a shell, an explosive charge in the shell having a fuse extending outside of the shell, said shell having a weakened section adjacent said charge for the purpose 55 described.

2. In a safety firecracker, in combination, a tubular shell having a compartment there- 60 in containing an explosive, and a weakened portion in said shell adjacent said compart- ment.

3. In a safety firecracker, in combination, a tubular shell, partitions defining a com- 65 partment in said shell explosive material and a fuse in said compartment, a weakened por- tion between the compartment and the re-

mainder of said tube, said tube being pro- 70 vided with a gas vent.

4. In a safety firecracker, in combination, a disruptable tube, means defining a com- 75 partment in said tube, explosive material and a fuse in said compartment, to provide a gas vent and a weakened wall section.

5. In a safety firecracker, in combination, a disruptable tube, an explosive therein and means weakening said tube to prevent dis- 80 ruption of a part thereof.

6. In a safety firecracker, in combination, a disruptable tube, an explosive confined in a part of said tube, and means integral with the tube to limit the disruption of said tube 85 to the part adjacent said explosive.

7. In a safety firecracker, in combination, a disruptable tube, an explosive confined near one end of said tube, a weakened wall in 90 said tube near said explosive and a parti- tion in said tube beyond said weakened wall.

8. In a safety firecracker, in combination, a disruptable tube, an explosive confined near one end of said tube, a weakened wall in said tube between said explosive and the 95 opposite end of said tube, a partition in said tube between said weakened wall and said opposite end, said tube being provided with a gas vent between said partition and weak- ened wall.

9. In a safety firecracker, in combination, a disruptable tube, an explosive confined near one end of said tube, a weakened wall in said tube between said explosive and the opposite end of said tube, a partition in said 100 tube between said weakened wall and said opposite end, said tube being provided with a gas vent between said partition and weak- ened wall, said gas vent serving to weaken 105 said wall.

10. In a safety firecracker, in combination, a disruptable tube, a closure near one end of said tube, a fuse through said closure, a partition spaced from said closure, explosive material between said closure and partition, 110 a second partition in said tube, said tube being provided with a weakened wall between said partitions for the purpose described.

11. In a safety firecracker, in combination, a disruptable tube, a closure near one end of said tube, a fuse through said closure, a partition spaced from said closure, explosive material between said closure and partition, a second partition in said tube, said tube being provided with a vent weakening 115 the wall thereof and allowing the escape of gases.

12. In a safety firecracker, in combination, a disruptable tube, a closure near one end of said tube, a fuse through said closure, a partition spaced from said closure, explosive material between said closure and partition, a second partition in said tube, said tube being provided with a vent, the walls 125 of which are inturned to provide a stop for 130

one of said partitions and also to weaken the wall of said firecracker.

13. A cap or closure for firecrackers or the like comprising a cup-like structure having a reflexed bottom.

14. In a firecracker, in combination, a shell, a closure therein of cup-like formation,

a reflex bottom in said closure and a weakened portion in said shell adjacent said closure.

In testimony whereof I hereunto affix my signature.

KOBY KOHN.
